Primary Examiner — Jonathan J Han(74) *Attorney, Agent, or Firm* — NKL Law; Jae Youn Kim(57) **CLAIM**

The ornamental design for a shoe sole, as shown and described.

DESCRIPTION

FIG. 1 is a perspective view of a shoe sole, showing my new design;

FIG. 2 is a front elevation view thereof;

FIG. 3 is a rear elevation view thereof;

FIG. 4 is a left side section view thereof;

FIG. 5 is a right side section view thereof;

FIG. 6 is a top plan view thereof; and,

FIG. 7 is a bottom plan view thereof.

The broken lines in the drawings depict portions of the shoe sole that form no part of the claimed design.

1 Claim, 5 Drawing Sheets(56)
